Parrot Bepop 2. dated 2016. found online [Nov. 12, 2015] <https://www.parrot.com/us/drones/parrot-bepop-2-fpv#technicals>.*Primary Examiner — Robert M. Spear*Assistant Examiner* — Marissa J Cash(74) *Attorney, Agent, or Firm* — Marshall, Gerstein & Borun LLP(57) **CLAIM**

The ornamental design for a remote-controlled flying drone, as shown and described.

DESCRIPTION

FIG. 1 is a front, right-side, and top view of a remote-controlled flying drone showing the new design.

FIG. 2 is a front elevation view of the remote-controlled drone.

FIG. 3 is a top plan view.

FIG. 4 is a right-side elevation view.

FIG. 5 is a left-side elevation view.

FIG. 6 is a bottom plan view; and,

FIG. 7 is a rear elevation view.

The broken lines represent portions of the remote-controlled drone with removable bumpers that form no part of the claimed design. The dash-dot lines mark boundaries of the claimed design.
